(57) **CLAIM**

The ornamental design for a trim ring for digital camera, as shown and described.

DESCRIPTION

FIG. 1 is a perspective view of the top, front and left side of a trim ring for digital camera showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view of the camera, the trimmed ring not being visible; and,

FIG. 7 is a bottom plan view thereof.

The portions of the digital camera in broken lines are shown for illustrative purposes only and form no part of the claimed design.
